COMBINED BOTTLE, HOLDER, AND CAP

George J. Collinet, Chicago, Ill., assignor to Swiss Harmony, Inc., Chicago, Ill., a corporation of Illinois

Application October 16, 1956, Serial No. 43,368

Term of patent 14 years

(Cl. D58—26)

Fig. 2

Fig. 1 is a perspective view of a combined bottle, holder and cap embodying my new design; and

Fig. 2 is a top plan view of same.

The sides not shown are similar to the sides illustrated.

I claim:

The ornamental design for a combined bottle, holder and cap, as shown and described.
